Geo. P. Kimmel.
ATTORNEY.

UNITED STATES PATENT OFFICE.

JOHN PETTIT, OF BARTLESVILLE, OKLAHOMA.

PUMP VALVE.

Application filed October 27, 1923. Serial No. 671,151.

To all whom it may concern:

Be it known that I, JOHN PETTIT, a citizen of the United States, residing at Bartlesville, in the county of Washington and State of Oklahoma, have invented certain new and useful Improvements in Pump Valves, of which the following is a specification.

This invention relates to a valve mechanism employed in wells in which sand and 10 the like is commingled with the fluid which is being pumped, and has for one of its objects to provide a simply constructed attachment whereby the sand and the like is prevented from settling or accumulating in the 15 valve chambers or upon the valve packings, or other parts, but will be constantly and automatically agitated and discharged with the fluid which is being pumped.

Another object of the invention is to provide 20 a device of this character in which means are provided for automatically agitating any sand or the like which may settle in the valve chambers during the time that the pump is not operated, and commingling it with fluid passing through the pump at the renewal of the operation and thus discharging it with the fluid.

Another object of the invention is to provide 25 a device of this character which may be adapted without material structural change to pumps of various forms or construction.

With these and other objects in view the invention consists in certain novel features of construction as hereinafter shown and 30 described and then specifically pointed out in the claims, and in the drawings illustrative of the preferred embodiment of the invention—

Figure 1 is a vertical section of the improved device.

Fig. 2 is an enlarged plan view of the centering device for the tubular conductor member.

Fig. 3 is a plan view of the combined coupling and bottom of the sand chamber with the agitating tubes in position.

Fig. 4 is a side elevation, partly in section, of the parts shown in Fig. 3.

In most oil wells, and the like, quantities 50 of sand are commingled with the fluid, and

being heavier than oil, settle on the pump parts, and unless removed or discharged with the oil, seriously damage the packings or cups on the working valves and rendering it necessary to "pull" the pump valves to 55 renew the packing, at frequent intervals, which is a serious obstacle and a source of annoyance and expense.

With the improved attachment herein shown and described, the sand or the like 60 which may be commingled with the fluid being pumped is constantly and automatically agitated and thereby prevented from settling in the valve chambers or upon the valves or the packing, but is discharged 65 with the flow through the pump.

The improved device may be adapted to various forms or construction of pumps, but for the purpose of illustration is shown applied to the operating valve portion of a 70 conventional pump structure, comprising a lower barrel member 10 having a wear lining member 11, the members 10 and 11 being coupled to a lower coupling ring 12, in which the upper end of the tubing anchor is 75 connected and represented at 13. Threaded into the coupling ring 12 is tubular wear or lining member 16, and threaded upon the upper end of the wear member is a guide sleeve 16', and coupled to the upper end 80 of the lower barrel 10 is a sleeve 15 which is closed at the upper end except for a relatively large central internally threaded opening to receive the lower end of a tubular member 16, and a plurality of smaller 85 openings encircling the larger central opening.

Coupled to the upper end of the sleeve 15 is an upper barrel member 18, the latter being coupled at its upper end by a collar 19 90 to the well tube, a portion of which is represented at 20.

At its upper end the tube 16 is coupled to a perforated annular centering member 21.

Fitting within each of the apertures of the 95 member 15 is a relatively small tube 22, each of the tubes being turned over into a half circle with the discharge ends pointing downwardly, as shown in Figs. 1 and 4. Any required number of the tubes 22 may be 100

employed, but for the purpose of illustration six of the tubes are shown uniformly distributed around the tube 16 and uniformly spaced between the latter and the 5 upper barrel member 18. The tubes 22 are of varying lengths so that their downwardly directed discharge ends are spaced at correspondingly varying distances from the upper face of the coupling member 15, as 10 shown in Fig. 4, the object to be hereafter explained.

Seated in the lower part of the wear tube 11 is the lower or stationary valve casing represented as a whole at 23 and including 15 an upwardly opening valve 24 of globular form, for illustration.

Bearing upon the centering member 21 is a stuffing box device represented as a whole at 29, and vertically movable through the stuffing box is a tubular conductor member 30, the latter coupled at its lower end in the valve casing 41, and coupled at its upper end in a head member 31. The head member 31 is provided with the usual tapered 25 threaded stud indicated at 32 to receive the coupling member 33 of the polish rod, a portion of which is represented at 34. The head member 31 is hollow and provided with a plurality of lateral apertures 35, inclined 30 downwardly and outwardly, and the upper end of the conductor 30 is formed with a valve seat to receive a valve 36, the latter yieldably held on its seat by a spring 37, as shown.

35. The parts 10, 11, 12, 13, 15, 16, 18, 19, 20, 21, 23, and 29, are stationary, and are mutually rigidly supported.

The movable or plunger portions of the pump comprise a lower valve casing represented as a whole at 38 and including pack- 40 ing elements 39 and valve 40, an upper valve casing represented as a whole at 41 and including a plunger element 42 and valve 43. The members 42, 43 and 30 are tubular and 45 the casing 41 is smaller than the barrel member 11 so that the larger amount of the liquid will pass laterally from the casing 41 through the usual lateral slots therein.

The mass of the liquid will pass into the 50 chamber 14 and through the tubes 22 and thence through the openings in the centering device 21 into the upper barrel 18 and into the main well tube 20. In the meantime the oil which passes through the tubes 22 is directed downwardly toward the upper face of the member 15 and commingles with the upwardly flowing oil and constantly agitates the latter and effectually prevents any sand or the like from settling in the chamber 14 55 and upon the valves or their packings.

When the pumping is stopped for any length of time, for instance at night, the sand is liable to settle in the space between the members 16 and 18, and when the pump 60 is again started, the downward flow through

the passages 35 will quickly and effectually displace such settling and cause them to commingle with the upwardly flowing oil and be discharged therewith.

Thus any sand or the like which may be 70 pumped up with the oil will be constantly kept in motion in the flowing oil and effectually prevented from settling upon the valves or other parts, but will be carried up with the oil and discharged therewith.

If the flow of the fluid through the tubes 22 is not sufficient to produce the requisite agitation to prevent all of the sand from settling in the chamber or should the "settlings" when the pump is not working, be 80 sufficient to fill the chamber above the discharge ends of the tubes 22, then the relatively strong flow through the downwardly directed discharge apertures 35 against the 85 settling will soon clear the chamber, as before described.

Ordinarily the flow through the tubes 22 will be sufficient to maintain the requisite agitation to prevent the sand from settling, but if under abnormal conditions the tubes 22 are not able to produce the required result, then the flow through the apertures 35 will supplement the action of the tubes, thus serving as an emergency agent, to prevent 90 failure of the action of the other parts. By arranging the discharge ends of the tubes 22 at different distances from the top of the member 15, if the settling accumulates to a sufficient extent to clog the shorter tubes, the 95 longer tubes will soon clear the obstruction.

100. The improved device is simple in construction and can be adapted without material structural change to pumps of various forms.

The preferred embodiment of the invention is disclosed in the drawings and set forth in the specification, but it will be understood that modifications within the scope of the claims may be made in the construction without departing from the principle of the invention or sacrificing any of its advantages.

Having thus described the invention, what is claimed as new is:

1. The combination with a pump, including the barrel and the intake and discharge valves, of a plurality of conductor tubes adapted to be supported within the pump barrel and between the valves in position to receive a portion of the liquid flowing therethrough, the discharge ends of the tubes being directed toward the intake valve.

2. A device of the class described comprising a tubular valve stem adapted to be coupled to a valve, and having lateral discharge passages, said stem adapted to receive a portion of the liquid flowing through the valve and discharging it through said passages and against said flowing liquid.

3. A device of the class described com-

prising a tubular valve stem adapted to be coupled to a valve, and having lateral discharge passages, said stem adapted to receive a portion of the liquid flowing through the valve and discharging it through said passages and against the said flowing liquid, and a plurality of conductor tubes adapted to be supported in position to receive another portion of the flowing liquid and discharging it toward the valve. ¹⁰

In testimony whereof, I affix my signature hereto.

JOHN PETTIT.
